UNITED STATES PATENT OFFICE.

GEORGE F. BRYANT, OF CHICAGO, ILLINOIS, ASSIGNOR TO ELECTROGRAPH ADVERTISING SERVICE, INC., OF CHICAGO, ILLINOIS, A CORPORATION OF ILLINOIS.

PRINTING PRESS.

Application filed November 8, 1923. Serial No. 673,434.

This invention relates in general to printing presses and has for its principal object the provision of a practical printing press adapted for a change of type at each printing impression.

A further object of the invention is the provision of a printing press of this character which will permit of the printing of a different name or name and address at the time it prints other matter, as the page of a catalog, part of a booklet, etc.

Another important object of the invention is the provision of a press of this character of high output, simple construction, and composed of parts unlikely to require frequent repair, replacement or readjustment, and which may be operated by the usual labor available without special or protracted instruction.

The invention contemplates the provision of a printing press wherein the substituted characters will print in exact uniformity with the unchanged characters and all will be either of type printing or all of typewriter printing or continuations thereof. The invention is adapted, of course, for varied salutation and address as required in circular letters, dodgers, and the like.

Numerous other objects and advantages of the invention will be apparent as it is better understood from the following description, which, taken in connection with the accompanying drawings, discloses a preferred embodiment thereof.

Referring to the drawings,

Figure 1 is a front view of a press embodying my present invention;

Fig. 2 is a top plan view thereof;

Fig. 3 is a rear view thereof;

Figs. 4 and 5 are side views looking from opposite sides;

Fig. 6 is an enlarged partial section taken substantially on the line 6—6 of Fig. 1;

Fig. 7 is a similar view taken in the same position but showing the parts in different arrangement as an incident to the printing action;

Fig. 8 is an enlarged fragmentary view partially in plan section;

Fig. 9 is a similar fragmentary view of the slug feed and attendant parts;

Fig. 10 is a partial enlarged section taken substantially on the line 10—10 of Fig. 2;

Fig. 11 is a partial enlarged section taken substantially on the line 11—11 of Fig. 2;

Fig. 12 is a front elevation of the chase; Fig. 13 is an enlarged partial section taken substantially on the line 13—13 of Fig. 7; and

Fig. 14 is a perspective view of a slug group.

For the purpose of illustrating my invention I have shown on the drawing a printing press in which it is embodied. This press has a base 25 of suitable construction and which will not be described in detail except as may be necessary to an understanding of the active parts of the apparatus. The base supports a press bed 26, which is vertically arranged in the present instance and upon which a chase 27 is secured in suitable fashion. The detail of the chase is shown in Fig. 12 from which it will be noted that the chase has the usual outside and inside walls adapted to contain a type bed 28, spacing members 29 and 31 and chase locks 32. On Fig. 12 I have shown at 33 a bracket or box setting off a space 34 at which the type having a single use is to print. This box is locked in the chase in the makeup as will be readily understood.

When the chase is positioned upon the bed 26 of the press this box is brought in registration with a plate 35 having an aperture 36 with which the box 33 registers, so

that an opening is provided through the bed and through the chase for positioning and printing of the slug or slug groups to be changed at each printing impression. A

magazine 41 for holding a supply of slugs or slug groups to be printed is mounted upon a cross frame member 42 behind and above the slug group printing position and a similar magazine or receptacle 43 is arranged adjacent thereto to receive each slug or slug group after printing. The magazines 41 and 43 are inclined respectively downwardly to and from their lower ends which are spaced apart to permit a slug carrier to be

arranged therebetween and to simultaneously receive a slug or slug group from the delivery magazine and feed out previously printed slug or slug group to the receiving magazine see Fig. 8. The slug carrier has a curved movement down from between the magazines and then is carried bodily along a right line into printing position. During the curved movement it is rotated to

turn the slug groups at 90° to their original position.

105

110

115

120

125

130

135

The slug carrier and its actuating mechanism will now be described. A slide 44 is mounted in horizontal ways 45 in the press frame and this slide is provided with a rotatable shaft or pin 46 having bearings at 47 (Fig. 9) in the slide. Between these bearings is arranged a sleeve 48 carrying a forwardly extending arm 49. A shaft 51 is arranged longitudinally of this arm and extends out beyond its end and is provided with a slug carrying head 52. Two side walls 53 fixed to the side of the head extend up and engage opposite sides of the slug group 54 as seen in Fig. 9. Viewing Fig. 7, which shows the arrangement of the press at the instant of printing, it will be understood that the slide 44 is moved to the left after the printing is accomplished and the slug carrier head is then swung upwardly about the pivot 46 to bring the slug group between the ends of the magazines.

These motions are accomplished through a train of mechanism, which will now be described. A motor 61 is mounted upon the base of the machine and through its pinion 62 drives a gear 63 upon a shaft 64, and a gear 65 upon this shaft meshes with a gear 66 upon a shaft 67 which carries a cam 68, which cam actuates both the slide in its movement and the upward and downward action of the slug carrier. A lever 71 is pivoted at 72 in the frame of the press and has a follower roll engaging in cam groove 73 on one face of cam 68. This lever is connected at its opposite end through a link 74 with the tail 75 of the slide. The link 74 is composed of two parts threadedly engaged, the outer one of which is split and adapted to be locked by set screws 76, the purpose of this last being to permit adjustment of the parts. The lever 71 in its movement moves the slide 44 as already described.

The arm 49 is caused to swing upwardly to discharging position by rearwardly extending lugs 81 upon shaft 46 between the ends of which is pivoted a link 82 in turn connected with the end of a lever 83. The lever 83 is pivoted on shaft 64 and has a follower roll 84 engaging in a cam groove 85 upon the opposite face of cam 68. It will be manifest that under the action of this cam downward movement of the lever 82 from the position shown in Fig. 7 will pull down upon the lugs 81 and swing up the arm 49 to discharge position.

The connection between the link 82 and lever 83 is a yielding one and includes a bolt 87 positioned through a tail 88 of an eye-bolt passing through a sleeve 89 adjustably fixed in a slot 91 in the end of the lever 83. The bolt is embraced by a sleeve 92 between the bolthead and the eye bolt and by a spring 93 beyond the eyebolt. The bolt is threaded into an end 94 of link 82 and is

locked in adjusted position by a pin or set screw 95.

Fig. 6 shows the slug carrier in receiving position and it will be noted that the side plates 53 are arranged at right angles in this position to the position they occupy when the slug group is in the chase. This turning is accomplished during the arcuate or lifting movement of the arm 49. A spring 90 fixed at one end to the shaft 51 and at the other end to the arm itself tends to rotate or pull the slug carrier into the position shown in Fig. 6 on the up-stroke of the slug carrier. On the down-stroke a cam 96 engages a roll 97 mounted on a stud shaft 98 carried by a bracket 99 extending up from the slide 44. As the arm 49 is swung down the cam 96 engages the roller 97 and the slug group is turned throughout 90°. The slugs are fed out of the delivery magazine or chute into the carrier and from the carrier into the receiving magazine as will be now described.

After each printing impression the slug carrier comes into position between the two magazines with the slug or slug group from which impression has just been taken. The two ends of the slug magazines and the carrier itself form a channel in which at this time two slug groups are resting, namely, one in the delivery magazine and one in the carrier, see Figs. 7 and 9. A pusher rod is moved transversely against the slug group at the bottom of the delivery magazine and pushes it toward and into the carrier, this slug group in turn pushing out the previously printed slug group into the end of the receiving magazine. Shaft 67 carries a bevel gear 101 which meshes with a bevel gear 102 on a shaft 103 mounted in the frame of the machine. This shaft is provided with a cam 104 in which is engaged a cam roll 105 of a lever 106 pivoted at 107 on the frame and connected by a link 108 with a lever 109 pivoted at 111 in the machine and having a bifurcated or slotted end 112 engaging a head 113 in which is mounted a rod 114 carrying a slug advancer 115. A second rod 116 carried by the head moves through suitable bearings to guide the slug advancer in its movement. A removable member or angle 117 is fixed on the advancer 115 to permit the apparatus to be adjusted for various thicknesses of slug groups by removing said member, or substituting others of different thickness.

Preparatory to this feeding action, the slug groups in the receiving magazine 43 are positively pushed along the magazine and out of the way of the slug group to be received. A bearing is provided upon a side of the arm 49, this bearing consisting of a casting extension 118, having a plurality of upstanding bearings 119 between which are mounted two or more fingers 121 fast on a

shaft 122 through the bearings. The fingers have abutments 123 (Fig. 6) engaging the casting extension 118 under the action of a spring 124 fixed to the shaft 122 and to the casting extension. The spring normally holds the shaft in position to press the abutments against the casting extension. When the slug carrier is raised to receiving and discharging position, the fingers move through suitable slots in the end of the receiving galley or magazine and push previously discharged slugs down this galley. Thereafter the slug, or slug group just printed is thrust endwise into the end of the receiving galley and upon the next down stroke of the slug carrier, the fingers ride back under this just received slug group, extending the spring until it may again return the fingers to normal position.

When the slug group has arrived at printing position, means independent of the slug feeding mechanism comes into action to hold it against the pressure of the platen. This means comprises two latches, or arms, 131 loosely pivoted on shaft 46. Each said latch or arm is provided with an abutment lug 132 adapted for engagement with and to drop behind fixed abutments 133 mounted on the frame adjacent the guides 145. When the slug groups arrive at printing position, these latches drop to behind the abutments into operative relation. After the printing operation, the arms or latches 131 are raised by two bell cranks 134 fast on a shaft 135 carried in the bearings 136 from the frame. Each bell crank has an end disposed beneath the end of its companion latch or arm 131 and a second end adapted for engagement by a tooth 137 upon a shaft 138 driven from the shaft 67 by gears 139 and 141 on said shafts respectively. After the printing impression is completed, rotation of shaft 138 lifts the bell crank and unlocks the carrier so that it may move to slug receiving position.

The printing impression is taken as will now be described. The frame is provided with a front extension 151 and upon this is mounted the platen 152 and its carrier 153. The platen is caused to bring the paper against the type by two arms 154 pivoted to a cross eccentric shaft 155 in the platen carrier 153 and two crank pins 156 upon crank disks 157 on the shaft 138 in suitable bearings 159 in the press frame. This shaft carries a gear 161 meshing with a gear 162 on shaft 67. The platen in its stroke swings down first to a vertical position and then is moved forwardly on the printing stroke. The platen carrier is provided with an under surface which is flat from the front end at 163 to a point 164 therebehind and from the point 164 is curved upwardly as indicated at 165. A cam slot 166 is provided in the tail 167 of the carrier and a roll 168 engages

this slot and as the platen moves insures first the swinging and then the rectilinear movement of the platen already described, it being understood that the swinging of the platen is about the principal center of the shaft 155. In the printing action, the paper to be printed is of course placed upon the platen and a holding fly 171 pivoted at 172 in arms 173 extending down from the lower edge of the platen clamps the paper in place during the printing operation. The movement of the fly is governed by a pinion 174 on the fly meshing with a gear 175 pivoted in brackets 173 and fast to arm 176 carrying rollers 177 adapted to engage a bed surface 178 to cause the fly to clamp the paper in advance of the printing action and as a part of the downward swing of the platen to vertical position.

The printing press shown on the drawing is equipped with both inking rolls and ribbon for printing. The ribbon mechanism comprises a pair of vertical spool holders 179 for ribbon spools 181 see Fig. 6, these holders being each mounted in a socket 182 having an arm 183 carrying a guide rod 184 behind which the ribbon is arranged, the two guide rods acting to hold the portion of the ribbon between them in printing position. The guide rods are provided with bearings 185 at the top for the spool holders 179.

The ribbon is advanced as will now be described. The lower member of each spool holder is provided with a beveled pinion 186 meshing with a similar pinion 188 upon a cross shaft 187 having bearing in the socket members. The socket members are carried upon the ends of rods 191 see Fig. 4 having bearings at 192 in the frame, springs 193 causing the rods to move back after the platen has carried the ribbon forward. A spring ratchet drum 194 is mounted on the end of shaft 187 and is engaged by a pawl 195 on a collar 196 on the shaft. A cord 189 is wound on drum 194 and under the action of the spring ratchet drum, winds up on the printing stroke. On the return stroke the pawl causes shaft 187 to turn with the drum as the cord unwinds and the ribbon is advanced.

The inking mechanism will now be described see Fig. 10. An ink plate 201 mounted at 202 on the top of the frame is held in adjusted position against a supply roll 203 by set screws 204 arranged at intervals beneath the plate and adapted to bring the plate into such contact with the roll 203 as will insure the desired feed of ink. A transfer roll 205 is mounted in two arms 206 fast upon a shaft 207 in the top of the frame. This shaft is provided with an arm 208 connected by a link 209 with a crank 211 upon a shaft 212, which shaft carries a gear 213 meshing with a gear 214 on shaft 158.

An arm 215 see Figs. 5 and 10 forms a bell crank with the arm 208 and this arm is connected by a link 216 with an arm 217 loose on a trunnion 218 of roll 203. A pawl 219 engages a ratchet 221 on the roll to produce intermittent rotation of roll 203. In the ink feeding action the transfer roll 205 is swung up from the position shown in Fig. 10 into contact with the roll 203 and the roll 203 is then advanced to produce the ink feeding action. The mechanism for swinging up the transfer roll 205 consists in an arm 197 fast on the shaft 207 and engaging a crank pin 198 in a crank 199 movable with a gear 200 in turn meshing with a gear 196 on shaft 212. The action is such that the roll 205 arrives at the proper instance to receive the charge of ink from roll 203. The inking rolls are indicated at 222, four such rolls being provided in the present instance.

These rolls are mounted in a vertical slide 223 see Fig. 10, and they receive ink from rolls 224 and 225 mounted in the frame of the machine. Each of these last mentioned rolls is provided with a pinion 226—227 in turn meshing with a pinion 228 on a stub shaft 229. This pinion meshes with a gear 231 fixed on the trunnions of a distributor roll 232, each gear meshing with gear 200. Two idle rolls 233 are provided to convey ink from roll 232 to the two rolls 226—227. Gear 200 is provided with a cam hub 234 in which is engaged a cam roll 235 on a lever 236 pivoted at 237 on the frame and having an end at 238 engaging in a groove 239 of a disk 241 on the end of the shaft or trunnion of roll 232. As the parts rotate this mechanism causes the roll 232 to have a longitudinal movement as well as a rotary one for the distribution of the ink. A similar motion is given the rolls 224 and 225. Their trunnions are mounted in a head 242 at 243. This head is swung about its pivot 244 by a link or lever 245 pivoted at 246 on the frame and engaging the end of roll 232.

The slides 223 reciprocate upon vertical guides 251 having cam faces 252 at their tops see Fig. 6. The rolls are mounted in the slides in spring bearings indicated at 253, see Fig. 4 and the rolls engaging the cams are swung out against the pressure of the springs and ride down over the surface of the slides beneath the cam and across the face of the type. Two links 261 extend down over the slides and are connected to arms 262 on shaft 64 see Fig. 5. One of said arms 262 is connected by a link 263 with an actuating lever 264 pivoted at 265 on the frame and having a cam roll 266 engaging in a cam groove 267 of cam 268 on shaft 158.

The press is started into actuation through any suitable means for energizing the motor. It may be stopped quickly by a foot lever 271

pivoted at 272 and carrying a brake member 273 for engaging a fly wheel 274 on shaft 275 carrying a gear 276 meshing with a gear 277 on shaft 138. A spring 278 pulls the manipulative end of the lever upwardly (viewing Fig. 5) and against a stop 279. This stop and the insulated member 281 are preferably in the circuit for energizing the motor and the application of the brake therefore cuts off the power as well. Prevention 75 against the starting of the press again upon release of the lever is insured by the use of the usual starting rheostat.

In the press shown on the drawing and embodying my present invention, means are provided for permitting action of the press without printing and also without the feeding of the slugs. It has been mentioned that shaft 155 through the platen carrier is an eccentric one and when the parts are in 85 normal position the eccentric portion is arranged upon the side of the platen adjacent the type as indicated in Fig. 6. The parts are locked in this position by spring pins 291 receiving in a yoke 292 pivoted about 90 the main axis of the eccentric shaft. Cross pins 293 extend through these pins and through rocking arms 294 at each end of the shaft and connected by a handle 295. When this handle is pulled to the left (viewing Fig. 4) cam surfaces 296 see Fig. 7 on the rocking members 294 lift the pins and permit the eccentric to be swung back so that upon the forward stroke of the platen contact with the type does not result. This 100 action interrupts the slug feeding. An arm 301 is mounted to rotate with the yoke when the yoke is swung to move the eccentric. This arm is adapted to engage a lever 302 pivoted at 303 on the frame and engaged with a rod 304 slidable in bearings 305 and 306 arranged on the frame. The rod 304 carries an arm 307 engaging a clutch member 308 on shaft 103 so that when the platen is swung around to non-printing position the chain 110 of slug feed mechanism is interrupted.

The slugs are provided preferably in groups and to facilitate the feeding thereof I have shown in Fig. 14 a slug group arranged as a single unit. The individual slugs or linotypes are encased in a band 315 of sheet metal having its ends interlocked at 316 or otherwise suitably secured together.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a printing press, the combination of 130

1. In a bed, a chase provided with an aperture therethrough mounted on said bed, means on said bed forming a slug group feeding station, a slug group carrier, means for feeding a slug group from the feeding station to the carrier, and means for swinging the carrier from the feeding station to a position opposite the aperture in the chase and for thereafter moving the carrier forwardly to project the slug group into position, so that the printing characters thereof are in the plane of the printing characters in the chase. 70
2. In a printing press, the combination of a bed, a slug carrier, means for moving the slug carrier into printing position as an incident to each operation of the press, and means independent of said moving means for locking said slug carrier in printing position and against the printing pressure. 80
3. In a printing press, the combination of a bed, a slug carrier, means for moving the slug carrier into printing position as an incident to each operation of the press, and means independent of said moving means for locking said slug carrier in printing position and against the printing pressure, said last mentioned means including interlocking abutments. 85
4. In a printing press, the combination of a bed, a slug carrier, means for moving the slug carrier into printing position as an incident to each operation of the press, and means independent of said moving means for locking said slug carrier in printing position and against the printing pressure, said last mentioned means including abutments automatically interengaging when the slug carrier is in printing position. 90
5. In a printing press, the combination of a bed, a slug carrier, means for moving the slug carrier into printing position as an incident to each operation of the press, means independent of said moving means for locking said slug carrier in printing position and against the printing pressure, said last mentioned means including abutments automatically interengaging when the slug carrier is in printing position, and mechanism moving said abutments out of engagement after each printing impression. 95
6. In a printing press, the combination of a chase, a slug storage magazine, and a carrier adapted to receive slugs from said magazine and to position them in registration with said chase, said carrier being movable successively upon curved and rectilinear paths from said magazine to printing position. 105
7. In a printing press, the combination of a chase mounted in vertical position and providing a printing slug position, a magazine located above said printing position, and a slug carrier movable from said magazine down to and then into printing position. 110
8. In a printing press, the combination of a chase mounted in vertical position and providing a printing slug position, a magazine located above said printing position, and a slug carrier movable from said magazine down to and then into printing position, said carrier having also a rotary movement. 115
9. In a printing press, the combination of a delivery slug magazine, and a receiving slug magazine inclined in opposite directions, a carrier for receiving slugs from the one magazine before printing and delivering them to the other magazine after printing, and means moving the slugs from said delivery magazine to said carrier and from said carrier to said receiving magazine. 120
10. In a printing press, the combination of a receiving magazine, a slug carrier delivering slugs after each printing impression to said receiving magazine, and a slug advancer moving the slugs in said receiving magazine prior to each delivery of slugs from the carrier thereon, said advancer moving back beneath a subsequently delivered slug. 125
11. In a printing press, the combination of a bed, a chase mounted on said bed, a channel shaped chute for feeding slug groups, a channel shaped slug carrier having open ends, and means for shifting the carrier from the chase to the receiving station and for causing the channel portions of the carrier and feeding chute to register whereby to permit the transfer of a slug group from the feeding chute to the carrier. 130
12. In a printing press, the combination of a bed, a chase mounted on said bed and provided with an aperture, a channel shaped feeding chute adapted to contain a plurality of slug groups, a channel shaped slug group carrier, means for positioning the carrier with its channel portion in registry with the channel of the chute, means for feeding the slug group from the chute to the carrier, means for automatically swinging the carrier from the chute to a point opposite the aperture in the chase and for angularly turning the carrier during such movement, and means for thereafter projecting a portion of the carrier through the aperture of the chase to position the slug type in the plane of the printing characters in the chase. 135
13. In a printing press, the combination of a bed, a chase mounted on said bed, a slug group feeding means, a slug group carrier, means for pivotally mounting the carrier on the bed so as to cause said carrier to swing in a plane in its movement from the feeding means to the chase, said means including a second pivotal connection to permit said carrier to turn on its own axis during the swinging movement. 140
14. In a printing press, the combination of a chase, a slug group feeding chute, a slug group discharge chute spaced therefrom and in line therewith, a slug group 145

carrier, means for shifting the slug group carrier into position between the slug group feeding chute and discharge chute and into registry therewith, a means for feeding a fresh slug group from the feed chute into the carrier and for discharging a slug group from the carrier into the discharge chute, and means for thereafter shifting the carrier toward the chase.

15. In a printing press, the combination of a bed, a chase mounted on said bed, a feeding chute and a discharge chute carried by said bed and disposed with their mouths forming registering spaced apart guideways, a slug group carrier, means for positioning the slug group carrier in the space between said chutes and in position to receive a slug group, a pusher operating transversely to said chutes and in the guideways thereof, means for operating said pusher to shove a slug group from one of said chutes into said carrier whereby to cause said first mentioned slug group to shove the slug group in said carrier into said second mentioned chute.

16. In a printing press, the combination of a chase having a slug group receiving opening, a slug group receiving and supplying station holding thereon a plurality of slug groups in predetermined position, a slug group carrier, an automatic mechanism for feeding a slug group into said carrier and for moving said carrier to position said slug group into the chase opening, said mechanism including means for bodily turning the slug group during its movement from the supply station to the chase opening.

17. In a printing press, the combination of a chase provided with a slug group opening, a slug group supply chute containing a plurality of slug groups, a slug group discharge chute adapted to receive slug groups, said chutes being arranged in spaced apart relation, a slug group carrier having a pocket adapted to receive a slug group, a means for moving said carrier into position between the supply and discharge chutes, a means for transferring a slug group from the supply chute to the carrier pocket and for simultaneously ejecting a slug group from the pocket to the discharge chute, and means for moving the carrier to the chase.

18. In a printing press, the combination of a bed having a chase provided with a slug group opening, a slide mounted on said bed and adapted to reciprocate to and from said opening, said slide having a rotatable shaft thereon, an arm rotatable with said shaft, a second shaft rotatably mounted on said arm and provided with a slug carrying head forming a pocket for a slug group, a slug group supply station removable from said chase opening, an automatic means for moving said slide toward and from said chase

opening and for swinging said slide when removed from said chase opening toward and from said supply station and for angularly turning said slug carrying head during said swinging movement whereby to transfer a slug group from the supply station to the chase opening and to properly position the same therein.

19. In a printing press, the combination of a bed having a chase provided with a slug group opening, a guideway on said bed opposite said opening, a slide shiftably mounted on said guideway, said slide carrying a rotatable shaft, an arm mounted on said shaft and rotatable therewith, a second shaft carried by said arm, said second shaft having a head formed with a slug group receiving pocket, a slug group supplying station, means for reciprocating said slide toward and from said chase, means for swinging said slide from said chase to said supply station and from said supply station to said chase, a coil spring surrounding said second mentioned shaft to cause it normally to turn on its axis, and automatic means operable to reversely turn said second shaft on its axis against the tension of said spring.

20. In a printing press, the combination of a bed having a chase adapted to receive a slug group in its printing plane, a shiftable carrier adapted to receive slug groups, means for shifting said carrier to feed a slug group to said chase, a slug group chute, means for shifting the carrier into position adjacent said slug group chute and a pusher acting transversely to said chute and adapted to push a slug group from said chute into said carrier, said pusher having a removable member constructed and arranged to permit the advance by said pusher of slugs of various thicknesses.

21. In a printing press, the combination of a bed provided with a chase, a slug group receiving chute mounted on said bed and adapted to receive a series of slug groups, a carrier shiftably mounted on said bed provided with a pocket adapted to receive a slug group, means for shifting said carrier from said chute to said chase and reversely, means for ejecting a slug group from said carrier pocket into said discharge chute, and means on said carrier for pushing along said chute the slug group previously deposited thereon by said carrier.

22. In a printing press, the combination of a bed provided with a chase, a slug group discharging chute on said bed, a slug group carrier means for conveying a slug group from the chase to the discharge chute and for ejecting said slug group from said carrier onto said discharge chute, said means including a suitable number of fingers adapted to engage the slug group previously deposited on said discharge chute to move

it along said chute whereby to provide room for the discharge of the slug group being carried.

23. In a printing press, the combination of a bed provided with a chase, a slug group receiving galley provided with a suitable number of slots, a slug group carrier provided with a corresponding number of fingers passing through said slots, means for shifting said carrier from said galley to said chase and reversely, means for ejecting a slug group from said carrier onto said galley, said fingers being mounted on said carrier to yield in one direction only and constructed and arranged on the approach of said carrier to said galley to permit said fingers to pass through said slots and to move a slug group along said galley and thereafter to permit said fingers to yield on the reverse movement of said carrier away from said galley.

24. In a printing press, the combination of a bed having a chase, a guideway on said bed opposite a portion of said chase, a slide on said guideway, means for reciprocating said slide toward and from said portion of said chase, a slug group carrier mounted on said slide, means for reciprocating said slide to cause said carrier to approach and recede from said chase, and means for holding said carrier in printing position relative to said chase and against the pressure of the platen, comprising a latch carried by said slide, a stationary abutment carried by said bed, said abutment and latch being constructed and arranged to permit the latch to engage said abutment when said slide is in printing position, and automatic means for lifting said latch at a predetermined time in the operation of the slide.

25. In a printing press, the combination of a bed with a chase mounted thereon, a slide on said bed opposite a portion of said chase, means for reciprocating said slide toward and from said chase, a shaft on said slide, an arm on said shaft, a slug group carrier carried by said arm, means for swinging said shaft on reciprocation of said slide to shift said slug group carrier toward and from said chase, means for automatically shifting said slide toward and from said chase, a latch pivotally mounted on said shaft, a detent carried by said bed and adapted to engage behind said latch firmly to hold said slug group carrier in printing position, a bell crank pivotally mounted on said bed and having an arm adapted to underlie said latch and means for automatically operating said bell crank to lift said latch at a predetermined moment to release said latch and to permit the recession of the slug group carrier from the chase.

26. In a printing press, the combination of a bed provided with an extension, an eccentric shaft mounted on said extension, means for operating said eccentric shaft, a platen carrier mounted on said eccentric, said platen carrier being provided with an under surface flat at the front end and extending rearwardly a predetermined distance and thence curving upwardly, an extension on said carrier, a cam slot in said carrier extension and a roll carried by the bed and engaging within said slot whereby on movement of the platen the same swings forwardly into substantially vertical position and then moves forwardly in a rectilinear line into printing position.

GEORGE F. BRYANT.
